UNITED STATES PATENT OFFICE.

JAMES P. HILLARD, OF FALL RIVER, MASSACHUSETTS.

VALVE.

SPECIFICATION forming part of Letters Patent No. 234,573, dated November 16, 1880.

Application filed July 21, 1880. (No model.)

To all whom it may concern:

Be it known that I, JAMES P. HILLARD, of Fall River, in the county of Bristol and State of Massachusetts, have invented a new and useful Improvement in Valves; and I hereby declare that the following is a full, clear, and exact description of the same, reference being had to the accompanying drawings, forming part of this specification.

10 This invention has reference to hydrant and other valves by which the flow of water or other liquid is to be controlled.

15 The object of this invention is to produce a valve in which the passage for the liquid when open shall be unobstructed and, as near as possible, direct, which shall not be liable to injury by the sudden increase of pressure caused by shutting off suddenly the flow of water, and shall be kept tight by the water-pressure 20 exerted on the valve-disk.

25 The invention consists in providing the valve-case with holes or slits and placing on the same a valve-disk also provided with holes or slits and operated by a spindle and lever, as will be more fully set forth hereinafter.

Figure 1 is a view of the improved valve shown as a hydrant-valve and arranged so that it may be readily operated by the hand or foot. Fig. 2 is a sectional view of the valve, 30 and Fig. 3 a view of the valve-disk. Fig. 4 is a front view, and Fig. 5 a side view, of a modification of the valve.

In the drawings, *a* is the valve-case. *bb* are the inlet-holes, corresponding with the holes *b'* 35 in the valve-disk *e*. *c* is the sleeve supporting the stem *f* of the valve-disk *e*, and *d* is the discharge-opening of the valve.

The valve-disk *e* rests against the face of the valve, and is held against the face by the 40 pressure of water on the valve-disk. The valve-disk may be faced with Babbitt or other composition metal, so as to form a tight joint. The valve is operated by the partial rotation of the valve-disk, so as to bring the openings *b'* in the valve-disk opposite to the openings *b* in the valve-case when the valve is open, and is closed by bringing the solid parts of the valve-disk over the openings in the valve-case. To 45 operate the valve-disk with ease the lever *g* is secured to the valve-stem, and to hold the valve-disk *E* against the face of the valve-case

the spring *h* is inserted between the case and the lever. A spring-washer may be used in place of the spring *h*, or both may be dispensed with, as the pressure of the water against 55 the face of the valve-disk will keep the same in place.

i is an outer case, provided with the inlet, and is secured to the case *a*, so as to make a tight joint.

When this valve is used as a hydrant it is desirable that the valve shall be self-closing, and for this purpose I place the weight *k* on the lever *g*, and to limit the motion of the valve-disk I place the two stops *ll* on the 65 valve-case. The lever *g*, coming in contact with these stops, can move only from one side to the other.

In Fig. 1 the valve is shown used as a hydrant-valve, *m* representing the hydrant-pipe. 70 The valve is shown closed by the weight *k*, and the rod *n* is shown connected with the lever *g*, so that by raising the rod *n* the lever can be raised until it comes against the stop *l*, when the valve is wide open, the valve-disk 75 being partially rotated, so as to bring the openings *b'* opposite the openings *b*. As soon as the rod *n* is released, the weight *k* will close the valve by the partial rotation of the valve-disk, as is shown in Fig. 1. The lever may be 80 extended beyond the stem *f*, and the rod *o* may be secured so that the valve is opened by depressing the rod *o* and will close as soon as the valve is released by the balance-weight *k*.

When the valve is to be used for a tank-valve the ball *k*, instead of being a weight, is 85 made so as to form a float, and is connected with the opposite end of the lever *g*, so as to close the valve when the water in the tank is at the desired height.

This valve may be used for all purposes for which valves are used by constructing the lever *g* as a hand-lever and placing the coiled spring *h* around the stem, so that one end of the coiled spring rests against one of the stops 95 *ll* and the other against the lever, so that the torsion of the spring *h* will act in the same manner as the weight *k*, or a float, to shut the valve by partially rotating the valve-disk *e*.

Figs. 4 and 5 clearly show the application 100 of the spring to the valve, and also show the construction of this valve.

When the valve is used for a street-hydrant, or in a place where it is liable to freeze, a small outlet, *p*, is placed into the lower part of the valve, and the channel *r* is cut into the 5 valve-disk *e*, so that when the valve is closed the outlet *p* will be connected by the channel *r* with the discharge-opening *q*, and will drain the water from the valve, so as to prevent freezing.

10 When the valve is open the drain will be closed by the partial rotation of the valve-disk, moving the channel *r* on one side, as is shown in Fig. 3.

This valve is simple in construction. The 15 wear of the faces of the disk and valve-case will keep the same tight, and as the disk is rotated only slightly more than the width of the opening it is not liable to much wear. The valve is not liable to cut, as there is no thin 20 edge, as is used in ordinary valves; and as the supply is only cut off there is no water-hammer, such as is caused by the closing of spring-valves, and by which the whole system of piping is subjected to excessive strain. All 25 the parts are strong and durable, no leather or other perishable packing being required, and the valve is not liable to get out of order.

Having thus described my invention, I claim as new and desire to secure by Letters 30 Patent—

1. The combination, with the valve-casing provided with a valve-seat having openings *b* *b* formed therein, and a sleeve, *c*, extending from the rear face of the valve-seat through the chamber in the valve-casing, of the rotary 35 disk *e*, provided with openings *b' b'*, and stem *f*, attached to said disk and supported in the sleeve *c*, substantially as set forth.

2. The combination, with the valve-case *a* and the stops *l l*, of the disk *e*, stem *f*, and 40 lever *g*, constructed to open and close the valve, as described.

3. The combination, with the case *a*, provided with the stops *l l*, the outlet *d*, and the detachable case *i*, having the inlet of the disk 45 *e*, stem *f*, and lever *g* provided with a weight, float, or spring to hold the disk in the position when the valve is closed, and return the disk to this position when released, as described.

4. The combination, with the rotary disk *e*, 50 provided with the port *r*, of the valve-seat, provided with the two channels *p q*, substantially as set forth.

In witness whereof I have hereunto set my hand and affixed my seal.

JAMES P. HILLARD. [L. S.]
